ABSTRACT

A two part wad column for use in shotshells is provided which consists of an overpowder component comprising inner and outer concentric cylindrical walls attached to a skirted end plate and a shot container component comprising a cup-shaped shot container and a skirted end plate which abuts the outer cylindrical wall of the overpowder component.

SHOTSHELL WAD

The present invention relates to a wad column for use in shotshells and in particular to a wad column which results in improved ballistic characteristics.

By "wad column" is meant the cushioning means or mid-wad which is interposed between the propellant charge and the shot within a shotshell casing together with a cooperating shot-containing pouch or shot concentrator. The function of the mid-wad component is to transmit the pressure of the expanding gases from the ignited propellant to the shot charge contained in the shot container in such a way that maximum propulsion of the shot is obtained with minimum recoil effect to the shooter and without the undesirable result of shot "stringing" or "scattering" caused by excessive distortion of individual pellets in the shot charge when the cushioning effect of the wad is not adequate.

One object of the present invention is to provide a novel wad column which will improve the ballistic and other properties of shotshell cartridges.

Another object is to provide a wad column which is light in weight, economic to manufacture and which may be conveniently loaded into shotshells by automatic loading machinery.

Other objects will appear hereinafter.

The improved shotshell wad column of the invention comprises (a) a mid-wad having an outer flexible cylindrical wall and a spaced-apart inner concentric cylindrical wall of a length equal to or less than the length of said outer wall, an integral lower end plate at right angles to said inner and outer cylindrical walls, said end plate having an integral downwardly disposed tapered circumferential skirt, the said inner and outer cylindrical walls being tapered upwardly from their point of attachment to the said end plate, the said outer cylindrical wall being of a diameter less than the diameter of the said plate and said outer cylindrical wall having at least three longitudinal integral ribs thereon, the said ribs together with said outer cylindrical wall being of a diameter equal to or larger than the diameter of the said end plate, the whole of the said wad being adapted for telescopic reception in a shotshell cartridge case; and (b) a cup-shaped shot container having a cylindrical side wall and an integral lower end plate, said end plate having an integral downwardly disposed circumferential skirt, the said shot container being butted against the leading edge of the outer cylindrical wall of the said mid-wad, in such a way that the said outer cylindrical wall of the said mid-wad contacts an internal surface of the said downward skirt of said shot container.

The wad of the invention may be more fully understood by reference to the following drawing wherein:

FIG. 1 is a side view partly in section of a shotshell cartridge containing the wad column of the invention;

FIG. 2 shows a perspective view of the mid-wad of FIG. 1;

FIG. 3 shows a plan view of the mid-wad of FIG. 2;

FIG. 4 shows in cross section one type of shot container suitable for use with the wad of the invention;

FIG. 5 shows a perspective view of the base end of one embodiment of a shot container suitable for use in the wad column of the invention; and

FIG. 6 shows a cross section taken along the line A—A of FIG. 4.

Referring to FIG. 1 there is shown a conventional shotshell 1 which may be of paper or plastic containing a propellant charge 2 and a shot charge 3. Shot charge 3 is contained in shot container 4 having a gas-sealing skirt 4a. Molded plastic overpowder mid-wad 5 is interposed between propellant charge 2 and shot container 4. Wad 5 comprises an outer tapered cylindrical wall 6 and a concentric inner tapered cylindrical wall 7 integral with end plate 8. End plate 8 has a downwardly disposed tapered, circumferential gas-sealing skirt 9. As shown, inner cylindrical container 4 rests so that an inner surface of skirt 4a is on the upper rim of outer wall 6.

Referring to FIG. 2 the overpowder mid-wad is shown in perspective. Shown are outer tapered cylindrical wall 6 and

concentric inner tapered cylindrical wall 7 both integrally formed with end plate 8. The outer surface of outer wall 6 has integrally formed thereon ribs 10 and 11. At least 3 and preferably 4 such ribs are required to assist in maintaining the wad in a centered location within a shotshell and to minimize surface contact between the wad and the shotshell casing.

In FIG. 3, which depicts a downward view into mid-wad 5, there is shown the inner and outer concentric cylindrical walls 7 and 6 and integral end plate 8. Also shown are integrally formed ribs 10 and 11 on the outer surface of wall 6. Ribs 10 and 11 extend outward from wall 6 only to the diameter of end plate 8.

In FIGS. 4 and 6 there is shown a shot container 12 particularly useful to handloaders when employing the wad of the invention. The container 12 has at its base 13 a downwardly directed thin-wall tubular structure 14 with internal ribs 14A integral with base 13. Tubular structure 14 may be inserted into or over, but preferably over, cylindrical wall 7 of wad 5 to aid in the assembly of a hand loaded shotshell. This makes a "one piece" assembly which is easier to insert into the shell when using hand loading equipment.

In FIG. 5 there is shown a shot container 15 which is particularly suitable for use with the wad column of the invention.

In the embodiment shown, which is viewed from the base end, the gas-sealing skirt 16 comprises an extension of cylindrical wall 17 beyond end plate 18. Inward sloping, integral buttress ribs 19 are located at the junction of skirt 16 and end plate 18 and in an assembled shotshell are adapted to cause the abutting outer wall 6 of mid-wad 5 to turn inward upon contact therewith.

In the manufacture of a shotshell containing the overpowder wad of the invention, with reference to the figures of the drawing, the shotshell cartridge 1 containing the powder charge 2 is further assembled by inserting therein mid-wad 5. Mid-wad 5 is inserted with end plate 8 and gas-sealing skirt 9 adjacent to the powder charge 2. Integral ribs, such as 10 and 11 help maintain wad 5 centrally in cartridge 1. Mid-wad 5 may be made in a series of lengths for use with various combinations of powder and shot charges and the wad chosen will depend on the space available within the shotshell. The shot charge 3, contained in shot container 4, is loaded into the shotshell so that an inner surface of skirt 4a rests on the leading edges of cylindrical wall 6. It is generally recognized that the use of a shot container or pouch improves the density of shot pattern when the shotshell is discharged. After insertion of the shot charge, the mouth of the shotshell is closed in a conventional manner.

In the firing of the shotshell of FIG. 1, gases generated by the ignition of powder charge 2 are sealed by means of skirt 9 and propel wad 5 forward against the inertia of shot charge 3. As wad 5 moves forward, the tapered ends of wall 6 turn inward, guided by the skirted or buttressed base end of shot container 4, and collapse inward towards end plate 8. At the same time, outward pressure is exerted against skirt 4a forcing it outward against the walls of shotshell 1 to form a secondary seal against any gases which may have passed mid-wad 5. As the forward movement of wad 5 continues, wall 7 contacts the base of shot container 4 and in turn collapses towards end plate 8. The sequential collapse of walls 6 and 7 provide a unique and cooperative effect in cushioning the impact caused by the expulsion of the shot charge by the expanding gases. This cushioning has been found to provide ballistic properties which are superior to those found in shotshells of the prior art.

The material of construction of the wad of the invention is preferably low priced, low density polyethylene of a density of about 0.920 gms/ml. although other thermoplastics such as, for example, polypropylene and mixtures of polyethylene and polypropylene may be employed. Because of the relatively thin sections of the wad of the invention, particular economies may be enjoyed by virtue of rapid molding times and a maximum number of cycles per minute which are possible during fabrication. Because of the design of both the shot container and the mid-wad of the wad column of the invention, relative-

ly simple molding equipment may be used in their fabrication. Unlike the one piece wad columns of the prior art which requires large expensive multiple-cavity, slow acting molds, the present components may be made quickly and efficiently. Additionally, the small bulk and light weight of the wad reduces the recoil experienced by the shooter. This small bulk and light weight is due in large measure to double gas-sealing provided by the wad column, which function permits a substantial reduction in the mass of the wad column components.

The wad of the present invention assembled in a shot-shell as shown in FIG. 1 was tested against other commercially available shotshells and columns. The results of these tests are given in the Example and Table shown below.

EXAMPLE

A series of loaded shotshells containing the wad column of the invention as well as a series of loaded shotshell using wad columns found in well known and commercially available shot-shells were prepared for comparison purposes as follows. One hundred primed, empty, plastic 12 gauge shotshells were hand charged with 27.5 grains of propellant of the type normally used in field load shotshells. At random, 20 of these were selected to be used with the wad column of the present invention as shown in FIG. 1 of the drawing, and groups of 20 others were each assembled using wad components found in the shotshells of manufacturers A, B, C and D. After seating the wad columns to a common pressure, 282 hand counted No.6 hard shot pellets were charged into each shell. The loaded shells were crimped closed with a folded crimp and 10 shotshells of each lot were mixed together in a container and selected at random for test firing. At test firing the following characteristics were checked.

- a. The velocity of the shot over a distance of three feet at a distance of three feet from the muzzle.
- b. The pressure generated within the shotshell.
- c. The shot pattern of the shot pellets.

The velocity of shot was determined electronically and recorded in feet/second. The pressure was measured by means of the standard lead crusher test used in the industry and recorded in lead units of pressure (l.u.p.). The pattern was determined by counting the number of shot pellets falling within a 30 inch diameter circle at a distance of 40 yards from the muzzle. Pattern results were expressed as a percentage of the pellets falling within the target circle.

In addition, the remaining 10 loaded shotshell in each lot were fired randomly in a recoil testing Field Proof Gun. In this test, the 50 pound test gun is suspended by cross wires which permit the gun to move horizontally rearward in recoil at the time of firing. This rearward movement is recorded on a sliding scale. Such measured recoil may then be converted to momentum and expressed as such.

From the test data it is possible to show an average velocity for each 100 units of pressure. Such a comparison indicates the efficiency of a wad column system where the combination of low pressure and high velocity indicates a more efficient use of propellant by virtue of a more effective wad column.

The results of the tests are shown in the Table below.

TABLE

Shotshell sample	Wad weight (grams)	Velocity (ft./sec.)	Pressure (l.u.p.)	Velocity per 100 units of pressure	Pattern, percent shot in 30 in. circle at 40 in.	Recoil (inches)	Momentum
Present invention-----	1.932	1,294-(1,268-1,311)	10,240-(9,800-10,500)	12.64	82.2-(76.6-89.4)	10.59	112.5
Manufacturer A-----	2.820	1,248-(1,223-1,272)	10,640-(10,200-10,800)	11.73	76.2-(72.7-80.8)	10.76	114.3
Manufacturer B-----	2,097	1,274-(1,253-1,292)	10,220-(10,000-10,700)	12.47	80.1-(76.9-83.3)	10.65	113.1
Manufacturer C-----	2.323	1,280-(1,267-1,288)	10,810-(10,200-11,200)	11.84	79.4-(69.8-88.3)	10.75	114.2
Manufacturer D-----	2.700	1,294-(1,282-1,306)	11,530-(11,300-11,800)	11.22	78.4-(75.5-81.9)	10.97	116.5

It may be seen from an examination of the results in the Table that the shotshell sample of the present invention provides the best combination of results of all the samples tested. That is, for a given amount of propellant, the use of the wad of

the invention provided high velocity and low pressure together with a superior shot pattern. It can also be seen from the results obtained that if the weight of propellant charge was selected to produce the same velocity in all samples, more propellant would be required in all cases except Manufacturer D and in all cases the pressure would be higher than with the wad of the present invention. With reference to the "recoil" results, it can be seen that in all cases recoil was greater in the competitive samples. The effect of such recoil could be overcome by employing a heavier gun when using the competitive shotshells but this is generally undesirable for the sportsman or hunter.

What we claim is:

1. A shotshell wad column comprising:

a. a resilient thermoplastic overpowder mid-wad having an outer cylindrical wall and a spaced-apart inner concentric cylindrical wall of a length equal to or less than the length of said outer wall, an integral lower end plate at right angles to said inner and outer cylindrical walls, said end plate having an integral downwardly disposed, tapered circumferential skirt, the said inner and outer cylindrical walls being tapered upwardly from their point of attachment to said end plate, the said outer cylindrical wall being of a diameter less than the diameter of said integral end plate and said outer cylindrical wall having at least three longitudinal integral ribs thereon, the said ribs together with the said outer cylindrical wall being of a diameter equal to the diameter of said end plate, the whole of the said wad being adapted for telescopic reception in a shot-shell cartridge case; and

b. a resilient thermoplastic cup-shaped shot container having a cylindrical side wall and an integral lower end plate, said end plate having an integral downwardly disposed circumferential skirt, the said shot container being butted against the leading edge of the outer cylindrical wall of the said mid-wad in such a way that the said outer cylindrical wall of the said mid-wad contacts an internal surface of the said downwardly disposed skirt of said shot container.

2. A wad column as claimed in claim 1 wherein the circumferential skirt of the said cup-shaped shot container has integrally attached thereto inward sloping, spaced apart buttress ribs, said ribs also being integral with the underside of the said end plate.

3. A wad column as claimed in claim 1 wherein the said cup-shaped shot container has a central, downwardly disposed cylindrical wall integral with the said end plate, the said downwardly disposed cylindrical wall being adapted to telescopically engage the said inner cylindrical wall of the said overpowder mid-wad.

4. A wad column as claimed in claim 1 wherein the resilient thermoplastic is polyethylene of a density of about 0.92 gram per ml.
